UNITED STATES PATENT OFFICE.

GERARD BROOK RILEY, CARLTON COLLINGWOOD SHERMAN, AND HERBERT OCTAVIUS
MOCK, OF LONDON, ENGLAND.

SUBMARINE MINE.

1,295,067.

Specification of Letters Patent. Patented Feb. 18, 1919.

Application filed January 17, 1918. Serial No. 212,373.

To all whom it may concern:

Be it known that we, GERARD BROOK RILEY, commander R. N., CARLTON COLLINGWOOD SHERMAN, commander R. N., and 5 HERBERT OCTAVIUS MOCK, lieutenant-commander R. N. V. R., subjects of the King of England, residing in London, England, have invented certain new and useful Improvements in Submarine Mines, of which 10 the following is a specification.

This invention relates to moored submarine mines of the kind in which a plummet weight is used in conjunction with the sinker to effect release of the winding drum 15 of the mooring cable, and to maintain it in such condition until the plummet reaches the bottom, on which the drum becomes locked against rotation, the length of the plummet chain giving the depth setting of 20 the mine in the well known way.

The present invention consists of a device which normally, positively retains the plummet or plummet chain in such position that it can not function to release the winding drum, but which will operate to release the plummet to function in its approved manner at a predetermined depth or an appreciable time after launching the mine gear.

25 In a convenient form of the device according to this invention, the plummet is held up by a pivoted catch, or the like, which normally retains the plummet chain against paying out, and is connected to or controlled by a hydrostatic release device or to a suitable delay mechanism, which respectively operates when the mine gear sinks to a predetermined depth, or after a predetermined time after launching, to allow the catch to take up such a position as to release the plummet or plummet chain from the restraint originally placed upon it. The plummet weight can then fall freely to unlock the winding drum in the 45 sinker.

The accompanying drawings illustrate devices embodying this invention.

Figures 1 and 2 are elevations of two hydrostatically operated devices. 50 Figs. 3 and 4 are elevation and part section of a device comprising a delay action mechanism, Fig. 5 an elevation at right angles to Fig. 3 of a detail.

Referring now to Fig. 1, the plummet 55 weight 1 is suspended from a pivoted hook

or arm 2 which is adapted to be engaged and restrained from falling by a pivoted catch 3, the movement of which toward the releasing position is controlled by a spindle 4 of a hydrostat 5. The catch 3 may be provided with a slot 6, in which the pivot 7 of the catch engages, the pivot 7 being carried by a support 8 slidably mounted in a bracket 9. By this means the pressure transmitted to the spindle of the hydrostat 60 by the catch 3 can be adjusted thereby allowing of a certain amount of latitude in fixing the parts to the sinker. It will be obvious that by selecting the leverage of the arms of the catch 3, the pressure transmitted to the spindle in a direction transverse to its longitudinal axis may be made as small as is practicable. The whole of the device may be arranged as a unit on a support adapted to be secured to the sinker. 65

On the mine gear being launched, the plummet and sinker together with the mine, fall toward the bottom, and on the hydrostat 5 reaching its set depth, the spindle 4 is withdrawn from the catch 3, and the 70 weight of the plummet draws the hook 2 away from the catch to let the plummet fall freely to fulfil its normal functions in the well known way.

In the arrangement shown in Fig. 2, the 75 plummet 1 is suspended from a hook or arm 2' which is kept in place by a pawl or notched lever 3', controlled by the spindle 4 of the hydrostat 5. The hook 2' is preferably formed with a portion 2² coöoperating 80 with the tooth or notch 3² of the member 3'.

By suitably designing the hook 2', and pawl lever 3' the pressure transmitted to the spindle 4 of the hydrostat from the pawl lever 3' may be made very small. It is 95 obvious that the plummet could be suspended directly from the hydrostat spindle but this method is not considered satisfactory for practical application.

In the arrangement shown in Figs. 3, 4, 100 and 5, a delay action device 9 is employed, which may be of any known form, and set in operation either by hand when the mine gear is on the point of being launched or automatically by a suitable trip on the mine 105 rails, as the sinker is about to leave the rails.

In the example of the delay action shown in Fig. 4, the plummet is connected to a bifurcated member, hollow spindle or the 110

like 10, which is connected by a ball release or equivalent device 11 to a member 12 which is moved outward by the delay mechanism. The members 10 and 12 are mounted within a fixed guide member 13. The moving part 12 of the delay action device may be prevented from moving downward owing to the weight of the plummet or otherwise, before the moment of launching the mine gear, by a catch 14, which is withdrawn out of action by a pivoted trip or lever 15 which may be operated by a suitable part on the mine rails on the gear being launched or otherwise as desired. On the mine gear being launched, and the delay mechanism set in operation in the selected manner, the member 12 moves outwardly carrying with it the member 10; and as soon as the balls of the ball release device 11 can move to disconnect the members 10 and 12, such as when they are in a lower position than the lower end of the guide 13, the member 10 falls away from the member 12, and so allows the plummet to fall unlocking the winding drum.

The total buoyancy of mine and sinker can be arranged in relation to time of release, in order that release can take place after a predetermined time such as can be obtained by providing the sinker with inlet hole or holes to allow the water to enter more or less gradually to govern the rate of sinking of the mine and sinker and thus vary the moment of release of the plummet.

Having now particularly described and ascertained the nature of our said invention, and in what manner the same is to be performed, we declare that what we claim is:

1. A plummet release retarder comprising the combination with the plummet, of a releasable support for said plummet, securing means for said support and hydrostatic means adapted to release said securing means to trip said support and thereby release said plummet.

2. A plummet release retarder comprising the combination with the plummet, of a releasable pivoted member adapted to retain the plummet in inoperative position, an adjustable lever having a portion thereof formed to engage said pivoted member and hydrostatic means including a spindle, said spindle being adapted to engage said lever or to be withdrawn from said engagement

thereby to retain the plummet in inoperative position or to release the same respectively.

3. An improvement in submarine mines of the type including an anchor and a plummet, comprising releasable means for supporting said plummet, and hydrostatic means adapted to trip said releasable means.

4. A plummet release retarder comprising the combination with the plummet, of a releasable member adapted to retain the plummet in inoperative position, a lever having a portion thereof formed to engage said pivoted member and hydrostatic means including a spindle, said spindle being adapted to engage said lever or to be withdrawn from said engagement thereby to retain the plummet in inoperative position or to release the same respectively.

5. A plummet release retarder comprising the combination with the plummet of a releasable member adapted to retain the plummet in inoperative position, a lever having a portion thereof formed to engage said releasable member, and hydrostatic means for controlling said lever and thereby to retain the plummet in inoperative position or to release the same respectively.

6. A plummet release retarder comprising the combination with the plummet of a releasable member adapted to retain the plummet in inoperative position, an adjustable lever having a portion thereof formed to engage said releasable member, and hydrostatic means for controlling said lever and thereby to retain the plummet in inoperative position or to release the same respectively.

7. A plummet release retarder comprising the combination with the plummet of a releasable member adapted to retain the plummet in inoperative position, an adjustable lever having a portion thereof formed to engage said releasable member and hydrostatic means including a spindle, said spindle being adapted to engage said lever or to be withdrawn from said engagement thereby to retain the plummet in inoperative position or to release the same respectively.

Signed at London, England, this 30th day of November, 1917.

GERARD BROOK RILEY.
CARLTON COLEINGWOOD SHERMAN.
HERBERT OCTAVIUS MOCK.
